UNITED STATES PATENT OFFICE.

WILLIAM C. ETTERS, OF GROVER, NORTH CAROLINA, ASSIGNOR OF ONE-HALF TO JAMES A. WARE, OF SAME PLACE.

FERTILIZER-DISTRIBUTER.

SPECIFICATION forming part of Letters Patent No. 444,193, dated January 6, 1891.

Application filed July 8, 1890. Serial No. 358,065. (No model.)

To all whom it may concern:

Be it known that I, WILLIAM C. ETTERS, a citizen of the United States, residing at Grover, in the county of Cleveland and State of North Carolina, have invented a new and useful Fertilizer-Distributer, of which the following is a specification.

This invention relates to fertilizer-distributers; and it has for its object to construct a machine of this class which shall possess superior advantages in point of simplicity, durability, and general efficiency, and by means of which the fertilizing material shall be deposited directly in the furrow prepared for its reception.

With these ends in view the invention consists in the improved construction, arrangement, and combination of parts, which will be hereinafter fully described and particularly

pointed out in the claim.

In the drawings, Figure 1 is a perspective view of a fertilizer-distributer embodying my improvements. Fig. 2 is a longitudinal sectional view.

Like numerals of reference indicate like parts in both figures.

1 designates an ordinary plow-beam, provided near its rear end with a downwardly-extending stock or standard 2, to the lower end of which the plow-blade or furrow-opener 3 is secured in the usual manner. Brackets 4 connect the plow-beam with the standard, and are extended below and in rear of the latter to form bearings for the shaft or axle 5, carrying the drive-wheel 6, having a series of laterally-extending studs or pins 7. Straps or brackets 8, extending upwardly from the beam 1, support the hopper 9, which latter is also connected by the straps 10 with the handles 11. The hopper is mounted pivotally upon the screws 11^b, that connect the ends of the braces 8 and 10, and against the front side of the hopper bears a spring 12^b, which is suitably secured upon the beam in front of the

hopper. The lower ends of the handles are secured to the sides of the standard, and they are connected by rungs 12 and 13, the latter of which extends through the rear end of the beam 1.

To the upper side of the beam 1, directly in front of the hopper 9, is hinged the shoe or

chute 14, which extends rearwardly under the hopper and terminates a short distance in rear of the latter, and directly above the upper end of the tube 15, which is secured upon the rear side of the standard 2, and the upper end of which extends through the beam 1. The opening at the upper end of the tube 15 is partially surrounded by guard-flanges 16. To the under side of the shoe 14 is attached a downward and rearward extending arm 17, the lower end of which is bent so as to form a hook 18, adapted to be engaged by the pins or studs 7, extending laterally from the drive-wheel 6. Of said studs any desired number may be used, and they may be located any desired distance apart.

From the foregoing description, taken in connection with the drawings hereto annexed, the operation and advantages of my invention will be readily understood by those skilled in the art to which it appertains.

The material which is to be distributed is placed in the hopper and the machine drawn over the field, the draft being preferably applied to an ordinary clevis at the front end of the beam. A vibrating motion is imparted by the spring 12^b to the pivoted hopper, causing the latter to discharge its contents into the shoe and preventing it from clogging. When the wheel rotates, the pins 7 engage the lower hooked end of the arm 17, thus transmitting to the shoe 14 an oscillating or vibrating motion. The shoe receives the contents of the hopper, which it in turn discharges into the upper end of the feed-tube 15, by which it is conveyed to the furrow at a point directly in rear of the plow or furrow-opener. The loose soil which falls back into the furrow covers the fertilizing material and is pressed and compacted by the rim of the wheel 6.

In order to regulate the quantity of fertilizing material which shall be permitted to escape from the hopper through the shoe 14 and into the feed-tube, I mount upon the rear side of said hopper a vertically-movable slide 19, having a slot 20 to receive set-screws 21, by means of which it may be retained at any desired adjustment.

My improved fertilizer-distributer is exceedingly simple in construction and may be manufactured at a very moderate expense. It

is easily operated and may be readily gaged, so as to deposit any desired quantity of fertilizing material to any given space of ground.

I am aware that a fertilizer-distributer having a vibrating shoe to receive the material from the hopper and discharge it into a conducting-spout is not new, and such is not broadly claimed.

By my invention the shoe is hinged to the upper side of the beam and is independent of the hopper. The wheel 6 is journaled in brackets extending rearwardly from the beam and standard, and said wheel will thus serve as a covering device to compress the dirt over the fertilizing material dropped in the furrow formed by the opener 3.

Having thus described my invention, I claim—

In a machine of the class described, the combination of the beam, the standard, the feed-tube upon the rear side of the latter, the per-

foration in the beam forming an upward extension of said feed-tube, the hopper mounted pivotally between brackets connected with the beam and the handles, the spring mounted upon the beam and bearing against the front side of the pivoted hopper, the shoe hinged upon the upper side of the beam under the hopper and having a hooked arm, and the drive-wheel journaled between brackets extending in rear of the standard and having laterally-extending pins engaging the said hooked arm, substantially as and for the purpose set forth.

In testimony that I claim the foregoing as my own I have hereto affixed my signature in presence of two witnesses.

WILLIAM C. ETTERS.
